UNITED STATES PATENT OFFICE.

ERNEST H. VINCENT, OF OAKLAND, CALIFORNIA, ASSIGNOR OF ONE-HALF TO HERMAN CHRISTENSEN, OF SAN FRANCISCO, CALIFORNIA.

CONDENSER.

Application filed August 21, 1922. Serial No. 583,163.

To all whom it may concern:

Be it known that I, ERNEST H. VINCENT, a citizen of the United States, residing at Oakland, county of Alameda, and State of California, have invented new and useful Improvements in Condensers, of which the following is a specification.

This invention relates to a condenser and particularly pertains to a steam condenser 10 for use in connection with steam propelled automobiles and the like.

It is the principal object of the present invention to provide a condenser adapted to be used in conjunction with a steam engine and boiler providing propulsion means for an automobile, and which condenser is compact in its construction, efficient in operation, and so designed as to permit the various parts to be removed, inter- 20 changed and to be held in their operative positions without being strained, twisted, or otherwise placed under tension.

The present invention contemplates the use of a radiator structure supported at the 25 forward end of an automobile hood, and embodying a plurality of vertically extending air cooled tubes mounted in a manner to permit thorough circulation of air among the tubes and an efficient condensation of the aqueous vapor passing through 30 the condenser.

The invention is illustrated by way of example in the accompanying drawings, in which:

35 Fig. 1 is a view in front elevation showing the assembled condenser as mounted at the forward end of an automobile chassis, with parts broken away to more clearly disclose its construction.

40 Fig. 2 is a view in transverse vertical section showing the complete condenser.

Fig. 3 is an enlarged fragmentary view in elevation showing the means for increasing heat radiation of the tubes.

45 Referring more particularly to the drawing, 10 indicates a vehicle main frame, here shown as provided with a sub-frame 11 upon which a power plant is suspended. This plant may include a steam boiler, steam engine and condenser. The condenser with 50 which the present invention is concerned is mounted at the forward end of the frame and is embodied within a structure somewhat resembling that of the ordinary automobile radiator. This device comprises a

dome 12 mounted upon a supporting frame 13 to which the dome is bolted. The lower wall of the dome is formed by a separate tube sheet 14 through which a plurality of vertically extending condenser tubes 15 are 60 arranged. These tubes are spaced from each other and form a nest substantially rectangular in horizontal cross section. The tubes are each formed with helically arranged radiating fins 16. The lower ends of the 65 tubes extend through a bottom sheet 17 forming the lower part of the frame 13. This member is formed with a plurality of stuffing boxes 18 carrying glands 19. These glands act upon packing 20 to prevent leak- 70 age of the condensate from the reservoir structure 21.

Secured directly below the floor member 18 is an auxiliary tube sheet 22. This sheet 75 carries a plurality of tubes 22 which are in longitudinal alignment with tubes 15, but have their contiguous ends spaced a slight distance from each other. This construction permits the effect of long tubes to be obtained, while insuring that the tubes will 80 not be excessively distorted or twisted.

The extension tubes 22' project into a drain pan 23. This pan is secured within the reservoir 21 and is separate therefrom. The top of the pan, however, is opened so that 85 the condensate may flow into the reservoir structure 21. The pan forms a transverse partition within the reservoir 21 and provides compartments 24 and 25. Communication between these compartments is afforded 90 by tubes 26 extending completely across the lower portion of the pan. The reservoir structure 21 is formed with a rearwardly and downwardly inclined floor, at the lowermost end of which a water outlet pipe 95 27 is connected. This pipe 27 is connected with a pump for delivering the water to the boiler.

The bottom sheet 17 extends both forwardly and rearwardly of the condenser. The forward end of this plate is formed with a filler opening 28 above which a neck 29 is secured. A cover plate 30 may be detachably held in a closed position over the mouth of the neck. An overflow drain pipe 31 extends downwardly through the neck 29 and conducts any excess of water from the reservoir 21 to an opening in the bottom thereof.

It is desirable that the water in the reser- 110

voir 21 shall be maintained at a predetermined minimum level and in order to visibly ascertain the level of the water within the reservoir an indicator 32 is provided.

5 In operation of the present invention the condenser is assembled as shown in the drawing, the frame 13 being bolted to the dome 12. Exhaust steam is delivered to the dome through a connection 46. This steam passes 10 into the dome and flows downwardly through the condenser tubes 15. The condensate then passes out the lower ends of the tubes onto the lower tube sheet 22 and will thereafter flow through the tubes 22', into 15 the tank 23. As described, the tank 23 is maintained completely filled with condensate or fresh water which entirely surrounds the extension tubes 22'. By the provision of the extension tubes 22' steam forcing its way 20 downwardly through the tubes 15 must also pass downwardly through the tubes 22', as these tubes are completely filled with water, due to maintaining the tank 23 filled, the steam must force its way downwardly 25 through this condensate or fresh water, and then bubble up around the tubes, causing complete condensation of all exhaust steam passing into the condenser. Fresh water and the overflow from the tank may be 30 drawn off from the reservoir 21 through pipe 27 and pumped to the boiler. The amount of water within the reservoir 21 may be constantly determined by the indicator 32.

It will thus be seen that the invention here 35 disclosed provides a compact and efficient condenser adapted to have particular usefulness in connection with steam driven automobile equipment.

While I have shown the preferred form 40 of my invention as now known to me, it will be understood that various changes might be made in the combination, construction and arrangement of parts by those skilled in the art, without departing from the spirit of the 45 invention as claimed.

Having thus described my invention, what I claim and desire to secure by Letters Patent, is:

50 1. A condenser for use in combination with a steam driven automobile comprising an upper tube sheet, a tube nest rigidly suspended therefrom, a dome covering the up-

per end of the tube nest and into which steam may be delivered, a bottom tube sheet through which the tubes are yieldably supported, and an auxiliary tube nest communicating with the lower ends of the tubes and receiving the condensate therefrom. 55

2. A condenser for use in combination with a steam driven automobile comprising 60 an upper tube sheet, a tube nest rigidly suspended therefrom, a dome covering the upper end of the tube nest and into which steam may be delivered, a bottom tube sheet through which the tubes are yieldably supported, and an auxiliary tube nest communicating with the lower ends of the tubes and receiving the condensate therefrom, and a condensate pan into which said auxiliary tubes project. 65

3. A condenser for use in combination with a steam driven automobile comprising 70 an upper tube sheet, a tube nest rigidly suspended therefrom, a dome covering the upper end of the tube nest and into which steam may be delivered, a bottom tube sheet through which the tubes are yieldably supported, an auxiliary tube nest communicating with the lower ends of the tubes and receiving the condensate therefrom, a condensate pan into which said auxiliary tubes project, and a feed water reservoir within 75 which the condensate pan is mounted and into which it may overflow. 80

4. A steam condenser for automobiles and the like, comprising an upper dome communicating with the exhaust ports of a steam engine, a tube sheet detachably secured to the bottom of said dome, a tube nest extending through said sheet and being fixed thereto, the tubes of said nest being formed with radiating fins, a lower tube sheet fitted with stuffing boxes through which the various tubes of the nest extend and by which they are packed, an auxiliary tube nest secured beneath the main nest and with the two sets of tubes in longitudinal alignment, a condensate pan into which the auxiliary tube nest extends, a reservoir receiving the condensate pan, said pan forming a vertical transverse partition therein, and means for indicating the level of water within the reservoir. 95 100
